APPARATUS FOR INHIBITING TAR
POLYMERIZATIONAlois Cibulka, Highlands, and Maurice W. Mayer,
Baytown, Tex., assignors to Standard Oil De-
velopment Company, a corporation of Delaware

Application January 31, 1936, Serial No. 61,776

1 Claim. (Cl. 196—58)

This invention relates to improvements in the heat treatment of hydrocarbon oils in which polymerization of the tar separated from the oil during vaporization is inhibited.

It has been customary in the cracking of petroleum oil to subject the oil in a confined zone to elevated temperatures and pressures, after which it has been passed to a digestion zone where thermo-decomposition of the oil has occurred. The thus treated oil has been conducted from the digestion zone to a tar separator in which the oil is maintained quiescent to permit separation from the oil of tar formed during decomposition of the oil. The tar has been maintained exposed to the full heat of the main body of oil in the tar separator throughout the period of separation, with a result that a high rate of polymerization of the tar to form coke has occurred.

It is an object of this invention to minimize the amount of polymerization of the tar.

Other objects will be apparent from the specification and from the accompanying drawing, in which latter the figure is a longitudinal sectional view of a tar polymerization inhibiting pot attached to a tar separator.

Referring to the drawing, reference numeral 1 designates a tar separator of the conventional form, used for example in the tube and tank method of cracking petroleum oil. Tar formed by the pyrogenetic decomposition of the oil settles in the separator 1. The tar as it settles is conducted directly to a tar pot 3 connected directly to the bottom wall of the separator 1. The tar pot 3 comprises a container the upper portion 4 of which is provided with a radially extending flange 5, which is secured to a similar flange 6 carried by a tubular extension 7 dependent from the bottom wall of the separator 1. The tubular extension 7 can be approximately 20 inches in diameter. The base 10 of the container 3 is provided with a bottom closure 12 secured to a flange 11 on the base of the container. The container 3 is provided with a tubular member 15 protruding outwardly from an intermediate portion of the container 3. The tubular member 15 is closed by a tubular extension 17. Member 15 and extension 17 are provided with radially extended flanges 18 and 19 respectively, whereby they are secured together. Tar as it separates in separator 1 falls into the container 3. The container 3 is of lesser diameter than the tar separator 1.

The level of tar is maintained at an intermediate position in the tar pot 3 through the

following arrangement of parts. Discharge line 25 leads from the bottom wall 12 of the tar pot 3. The discharge line is provided with a fluid pressure valve 27. Valve 27 is a diaphragm control valve comprising a diaphragm 29 which extends transversely across a fluid tight casing 30. The valve 27 is connected by means of a piston 31 with the diaphragm 29. The valve 27 is normally maintained closed by means of a helical spring 32. The valve 27 is actuated by means of compressed air, or other fluid, in a way to be later described.

The level of tar in the tar pot 3 is controlled by a float 37, which rests upon the surface 38 of the tar. The float 37 is attached to one end of a rod 40, the opposite end of which carries arm 41 which is pivotally mounted in the extension 17. Rise or fall of the float 37 with rise or fall of the level of tar in the tar pot 3, therefore, causes rotary movement of the arm 41. This rotary movement of the arm 41 is caused to control the supply of air to actuate the valve 27, as follows. An air line 44 leading to the casing 30 of the diaphragm valve 27 is connected to a pilot valve 46. The pilot valve 46, which is of well known construction, is provided with a trigger 50 mounted for reciprocation longitudinally to open or close the pilot valve. Rotation of the arm 41 is caused to effect longitudinal reciprocation of the trigger 50, as follows. A crank arm 52 is radially connected to the arm 41. An adjustable link 54 is connected at one end to the crank arm 52 in spaced relation to the arm 41. The opposite end of the link 54 is pivotally connected to a lever 56, an intermediate portion of which is pivotally supported at 57. The lever 56 carries a head 60 mounted for engagement with the trigger 50 to effect longitudinal reciprocation of the trigger 50 with change in level of the tar 38. The tar is maintained at the low level designated 38 in the tar pot in order that the interfacial surface will be relatively small, and any given surface quantity of liquid tar may be maintained in direct contact with the vapors in the separator 1 for a very small length of time. This feature permits of considerable cooling of the tar without appreciable condensation of cycle fractions which are in the vapor state. It will be noted that as the liquid level 38 rises the diaphragm valve 27 is caused to be open to allow the tar to flow out through the line 25.

The polymerization inhibiting pot is provided with a plurality of vertically spaced valve sample lines 63, 64, 65 and 66, which connect with a manifold 67. A valve line 68 leads from the

manifold 67, whereby samples of the contents of the polymerization inhibiting pot can be withdrawn for inspection. A valved line 69 and a valved line 69a are provided to admit cold flux 5 to the tar pot for flushing purposes when necessary. The flux may be admitted to the tar pot at a temperature of 700° F. or lower, to aid in inhibiting polymerization of the tar and, therefore, minimize the formation of coke. The valved 10 line 69a specifically performs the function of cooling the pivot 41 in order to minimize the formation of coke at this point as well as aiding in reducing the temperature of the tar within the pot 3.

15 By the procedure described, the tar level is maintained in a relatively small tar pot of, for example, 20 inches diameter, and the tar falls directly as formed into the pot. A cylindrical screen 72 protrudes into the tar separator 1 from 20 the tar pot 3, to prevent coke, concrete or the like, from falling from the separator 1 into the pot 3. The upper end of the tubular screen 72 is preferably open. The time that the tar must remain at the high temperature in the separator 25 equipment is reduced and, therefore, the amount of polymerization of the tar to form coke is decreased. Coke formation at the bottom of the separator 1 is almost completely eliminated.

By holding the liquid within the pot 3 and exteriorly of the separator 1, the surface of liquid tar in direct contact with the vapors in the separator 1 is very small. In view of the small interfacial surface, the cooling of the liquid with cold tar flux reduces the polymerization rate 30 without appreciable condensation of the heavier fractions in the vapor, and the tar gravity remains unchanged. The use of the particular form of tar pot illustrated provides an economical method of improving the operation of cracking coil tar separator, since it is necessary only 35 that a tubular extension 7, or nozzle, be driven into the bottom of the existing separator drum and the tar pot attached thereto. Furthermore, the float device 37 can be easily installed and 40 repaired through the lateral extension of the tar pot. The addition of the tar pot to an existing separator and the maintenance of the control level in the pot itself provides additional 45 effective separator height, since the tar level is moved farther away from the vapor outlet nozzle 50

leading from the separator 1. While the device has been described as applied to a separator used in the pyrogenetic decomposition of oil, it will be understood that it can be used in connection with any process for the heat treatment of oil in which tar is formed as a result of the treatment, and some of the advantages of the invention will be retained.

Various changes and alternate arrangements 10 may be made within the scope of the appended claim, in which it is our intention to claim all novelty inherent in the art as broadly as the prior art permits.

We claim:

An apparatus of the character described including a tar separating chamber adapted to receive cracked hydrocarbon products, a separate smaller tar pot secured to the bottom of said tar separating zone and in communication with said tar separating chamber for receiving tar from said tar separating chamber, said tar pot at its upper portion having a smaller cross sectional area than said tar separating chamber so that a smaller surface of the tar in said tar pot is exposed to the high temperature in said tar separating chamber, said tar pot having a hollow lateral extension, means for maintaining the level of the tar substantially constant at a relatively low level in said tar pot and at a substantial distance below said tar separating chamber, said means including a discharge valve for withdrawing tar from said tar pot, said discharge valve being operated by means responsive to the changes in the level of the tar in said tar pot, said level responsive means including a float arm pivoted in said lateral extension at a point removed from said upper portion of said tar pot, and means whereby a cool fluxing agent is introduced into said lateral extension of said tar pot adjacent said float arm pivot for cooling and flushing said pivot and for cooling the tar without appreciable condensation of the vapors above the tar in said tar pot, said smaller tar pot providing means whereby the time of contact between the tar in said tar pot and hot vapors in said tar separating chamber is relatively short and the rate of polymerization of the tar is reduced.
